UNITED STATES PATENT OFFICE.

WILLIAM FAIST AND JOSEPH FUX, OF MILWAUKEE, WISCONSIN, ASSIGNORS
TO FAIST, KRAUS & CO., OF SAME PLACE.

MACHINE FOR SIFTING AND SORTING FLOUR OR MEAL.

SPECIFICATION forming part of Letters Patent No. 484,306, dated October 11, 1892.

Application filed May 1, 1891. Serial No. 391,299. (No model.)

To all whom it may concern:

Be it known that we, WILLIAM FAIST and JOSEPH FUX, of Milwaukee, in the county of Milwaukee and State of Wisconsin, have invented certain new and useful Improvements in Machines for Sifting and Sorting Flour and Meal; and we do hereby declare that the following is a full, clear, and exact description thereof.

10 Our invention relates to machines for sifting and sorting meal and flour and will be fully described hereinafter.

In the drawings, Figure 1 is a longitudinal vertical section of our machine on line 1 1, Fig. 2. Fig. 2 is a transverse section on line 2 2, Fig. 1. Figs. 3, 4, 5, 6, and 7 are plan views of the various sieves and conveyers which form parts of our invention. Fig. 8 is a transverse section of a modification of our invention on line 3 3, Fig. 10. Fig. 9 is a detail. Fig. 10 is a longitudinal section on line 4 4, Fig. 8. Fig. 11 is a broken plan of the feed end of our machine; Fig. 12, a cross-section of the feed-pipe on line 5 5, Fig. 14. Fig. 13 is a cross-section of same on line 6 6, Fig. 14; and Fig. 14 is an end elevation of our machine.

15 A is the casing containing the sifting and conducting frames. Its top A' is removable and has an inlet A² for the admission of the stock to be operated upon.

B, B', B², and C are outlet-pipes that lead from various compartments made by the sieves and conductors.

20 On the bottom of the casing is arranged a pair of narrow conveyers D D, one on each side of the frame. These conveyers are made each with a stepped bottom a—that is, a bottom consisting of inclined rises and vertical faces—and each has a partition b at one end and an opening b' in it between this partition and that end of the frame to register with a like opening in the conveyer above it, as well as two partitions b² b³ at the other end and corresponding bottom openings b⁴ b⁵, also making channels from the upper sieves and conveyers, and an inner bottom opening b⁶, that leads to one of the spouts B².

25 Above conveyers D D is arranged another conveyer E, which is divided by partitions E' E² E³ into four longitudinal compartments 1

2 3 4. Compartments 1 and 4 have stepped bottoms, like conveyers D and D, but facing in an opposite direction, and these compartments have partitions e e' in their left-hand ends and openings e³ in their right-hand ends, while the center compartments 2 and 3 have partitions e² e² in their right-hand ends and their steps face oppositely to those in compartments 1 and 2 and terminate in openings e⁴ at the left.

Above the conveyer E is a conveyer-sieve F, which is constructed as follows: It is partitioned into four longitudinal compartments F', F², F³, and F⁴, which compartments have stepped floors of sifting material, the steps facing to the left in compartments F' and F⁴, while those in the floors of compartments F² and F³ face to the right. A partition g extends clear across the right end of the sieve F, and at this end, inside of the partitions, are transverse conveyers F⁵ F⁶, one F⁵ facing toward and extending through an opening in the partition from compartment F² to compartment F' and the other F⁶ from compartment F³ to compartment F⁴. The opposite ends of compartments F' and F⁴ open downward, and between each opening and the end of the sieve is a partition g'. Suspended in each of the compartments F' and F⁴ above the bottom are one or more channels or troughs h h, the bottoms of which are inclined from one side to the other, and above the space between these troughs and between their outer sides and the sides of the compartments may be arranged deflecting-shields h'. The channels h are closed at one end by a partition h³ and at its other end each opens over into outlet h⁴.

Above the conveyer-sieve F is a solid-bottom conveyer G, also having four longitudinal compartments G' G² G³ G⁴ and which has partitioned openings j across the left end of its central compartments G² and G³. The bottoms in all of the compartments are stepped to the right, and at the right end the two center compartments open downward, the opening in compartment G' being connected with the compartment G² by a transverse conveyer i through an opening in the adjacent partition, while a like conveyer connects the other two compartments.

H is the top conveyer-sieve. This, like the

conveyer G, is partitioned into four compartments $H' H^2 H^3 H^4$. The bottoms of the compartments are all stepped to the left and connected at the left by conveyers H^5 with downward openings H^6 . Each of the said compartments 1 to 4 of conveyer E is formed with transverse openings through its floors, in which fit solid slides $m m' m^2 m^3 m^4$, that extend through side openings in the casing, and across the compartments, just back of each slide, are partitions m^5 , which extend down nearly to the floor to divide the material that falls from the compartments F' and F^4 of sieve F, and the floor of each of these compartments consists of sifting material of varying mesh. For instance, one section may be covered by No. 8 material and the others by No. 6, 5, 4, 3, and 2 successively and according to the degree of mixture necessary for different grinds of wheat. Either or any of the slides $m m' m^2 m^3 m^4$ may be drawn out to admit the proper grade of flour directly from conveyer E to the lower conveyers D, from whence it is carried out through the outlet b^6 , while the rest is carried by the conveyer E to outlet C, and during this operation a fan J, the pipes of which enter the casing at J' , purifies the stuff by drawing air in through openings m^6 and up through the sifting-floors of compartments F' and F^4 of sieve F. The fluff rising between the troughs h passes out with the air, while the heavier impurities drop into the troughs and are conveyed off to outlet h^4 .

The casing A is designed to be hung from an upper support by swinging arms M and beneath is supported by a short shaft N, that is eccentrically ball-and-socket jointed to the hub of a fly-wheel O, so that by the revolutions of the fly-wheel the casing will be gyrated, and this gyration, in connection with the forms of the conveyer-floors, causes the material to travel, as described, during the sifting, purifying, and grading processes.

The inlet A^2 is provided with partitions A^3 , forming ducts, in which are openings $A^4 A^5 A^6 A^7$, that lead to the various sieves and conveyers, and to regulate the feed and control its distribution a cylinder composed of two sections $P P'$ is interposed between the mouth of the feed-pipe P^8 and the inlet. The lower section P' is formed with vertical partitions p , each of which is formed with triangular horizontal flanges, one p' at its top and another p^2 at its bottom, and just beneath the bottom flanges the inner ends of four triangular gates $q q' q^2 q^3$ are pivoted on a lug a^8 , that projects downward from the intersection of the partitions. The handles of these gates project through slots in the cylinder-section P' , and by them the gates are turned to cut off or admit stock to the various compartments of the inlet A^2 , according as the compartments a^2 between the partitions are opened or closed. In its top the section P has a register-wheel q^4 , having a handle q^5 and turning on a pin a^9 .

In the modifications, Figs. 8, 9, and 10, the arrangement of sieves may be the same as in Fig. 1, but the purifier portion of the apparatus is outside of the casing proper—namely, in attached casings R R, each of which contains conveyers D, and above which is another conveyer D', the floor of which corresponds in structure with the floors of compartments 1 and 4 of conveyer E, Figs. 1 and 2, in being stepped to the left and having transverse openings that are closed by slides $m m' m^2 m^3$ and side openings m^6 . Above this is a sieve D², which corresponds exactly with compartments F' and F^4 of sieve F, Fig. 5, and contains above its bottom channels h and has, also, the side draft-opening J' , and then above this in the main casing are the conveyers D³ and D⁴ and sieve D⁵.

Between the two attached casings R R is a fly-wheel S, which is formed with peripheral fans S', that make it also a fan-wheel. This is inclosed in a drum S⁴, having side outlet-openings s and a central opening in its top, that is connected by a flexible pipe S³ with casing A and by other flexible pipes S⁶ with the openings J' of the attached casings R, and the shaft N is eccentrically ball-and-socket jointed to the fly-wheel, as is the like shaft in Fig. 1.

Having thus fully described our invention, what we claim as new, and desire to secure by Letters Patent, is—

1. The combination, with the grader, of a fly-wheel and fan combined and its casing and flexible tubular connections between the casing and the grader.

2. The combination, with the inlet of the main casing, of partitions and ducts leading therefrom to the various sieves and conveyers and a divided inlet-pipe and pivoted gates, substantially as described.

3. In a chop-grader, the combination, with the frame and means for actuating the same, of a stepped conveyer-sieve in the frame, divided into four or more compartments, the steps of the respective adjacent compartments being arranged at opposite inclines, a stepped conveyer below the sieve at the end of the frame, movable slides in the end compartment containing the lower sieve, and troughs above the lower sieves, substantially as described.

4. In a chop-grader, the combination, with the frame, of a stepped conveyer-sieve there-in extending across the interior of the frame, conveyers at the ends of the frame, conveyer-sieves above the end conveyers, troughs above the sieve, and means for inducing air-currents through the sieve at the ends and above the troughs, substantially as described.

WILLIAM FAIST.
JOSEPH FUX.

In presence of—

S. S. STOUT,
F. W. BIGGAR.
